No. 731,979.

PATENTED JUNE 23, 1903.

C. E. TUDOR & O. B. KAISER.

FEED WATER HEATER AND PURIFIER.

APPLICATION FILED JUNE 26, 1902.

NO MODEL.

UNITED STATES PATENT OFFICE.

CHARLES E. TUDOR AND OLIVER B. KAISER, OF CINCINNATI, OHIO,
ASSIGNORS TO THE TUDOR BOILER MANUFACTURING COMPANY,
OF CINCINNATI, OHIO, A CORPORATION.

FEED-WATER HEATER AND PURIFIER.

SPECIFICATION forming part of Letters Patent No. 731,979, dated June 23, 1903.

Application filed June 26, 1902. Serial No. 113,251. (No model.)

To all whom it may concern:

Be it known that we, CHARLES E. TUDOR and OLIVER B. KAISER, citizens of the United States, residing at Cincinnati, in the county 5 of Hamilton and State of Ohio, have invented certain new and useful Improvements in Feed-Water Heaters and Purifiers, of which the following is a specification.

The object of our invention is to provide a 10 feed-water heater and purifier of simple and effective construction, whereby the heater will more thoroughly remove the impurities from the feed-water and at the same time can be easily kept in an efficient condition, 15 providing means for quickly heating the feed-water, readily separating out the impurities, and providing means for readily removing the impurities and keeping the heater in proper condition.

20 The features of our invention are more fully set forth in the description of the accompanying drawings, forming a part of this specification, in which—

Figure 1 is a central vertical section of our 25 improved heater and purifier. Fig. 2 is a section on line $\alpha\alpha$, Fig. 1. Fig. 3 is a section on line yy , Fig. 1. Fig. 4 is a sectional view of a pan.

The heater is formed of a single shell which 30 is divided into several compartments, as will be hereinafter explained.

A represents the steam-receiving chamber at the base of the heater.

B represents a central tube for conducting 35 the steam up to the heating and condensing chamber.

C represents the steam-inlet pipe; D D, the baffle-plates, which are preferably formed of corrugated iron, and two or more baffle-plates, 40 one in front of the other, are employed, so as to more readily and efficiently separate out the oil from the steam and conduct it off.

a represents partition-plates at the top of the steam-receiving chamber and which form 45 the bottom of a settling-chamber E.

b represents an annular pipe concentric with the pipe B, but forming an annulus between said pipe for the passage of water into the settling-chamber.

F represents an annular filter-chamber. It 50 is separated from the settling-chamber by a perforated plate or screen c. c' represents similar screens or plates for allowing the purified water to escape into the pure-water chamber G, which is vertically above the settling-chamber.

d represents a partition-plate covering the top of the pure-water chamber.

Upon pipe B is mounted a series of overflow heating pans or shelves. These parts are 60 constructed as follows: s represents brackets or legs mounted upon the flanged top of pipe B. H represents a deflector-plate which forms the base of the heating-pan system. This plate is preferably crowning, so as to 65 shed off the water which falls on the top side and forces the steam outward, causing it to pass out of the pipe and along the under side of said plate and forces it into immediate contact with the water. 1 2 3 4 represent overflow 70 shelves or pans, which are convex or dish-shaped and preferably constructed with a stem 5 and a socket 6, so that each pan will nest into the next succeeding one. The series of pans are clamped together by a central 75 bolt 7. 8 represents a manhole opposite the shelves for affording ready means of access, so that they may be readily taken out and cleaned of the impurities deposited thereon. These pans and their surrounding space in the 80 top portion of the heater form the heating and condensing chamber, the construction and arrangement being such that the steam is rapidly condensed by the water overflowing the shelves or pans and rapidly and efficiently 85 taking up the heat, the water passing down through the annular pipe b into the settling-chamber, from whence it passes by upper filtration through the filtering-chamber into the pure-water chamber, from which it is drawn 90 off through an outlet-pipe 9. Water is maintained at any desired level by means of a float in cage 10. 11 represents the stem of the float-valve connecting it to a cut-off valve in the globe 12. These parts are of ordinary 95 construction.

In order to remove impurities, a common blow-off pipe I is provided, having branch

pipes tapping the several chambers. K represents an oil-outlet pipe tapping the blow-off I, and it is preferably provided with the ordinary trap-valve, so that the oil is allowed 5 to flow off as fast as it is separated from the steam.

M represents a blow-off pipe tapping the settling-chamber E. N represents a similar pipe tapping the pure-water chamber. Q is 10 a similar pipe tapping the heater above the pure-water chamber.

R represents an overflow-pipe. This is just at the top of the normal water-level. Of course the cage 10 and float-valve could be 15 lowered and a level maintained as low as the top of the pure-water chamber.

In the operation of feed-water heaters and purifiers where the feed-water contains lime, magnesia, or similar impurities it is essential 20 to have a settling-chamber where the heavier deposits may be settled without necessitating their being passed through a filtering-chamber; otherwise the interstices of the filtering medium are rapidly filled up with the liberated 25 impurities, choking the operation of the heater and frequently requiring a stoppage of the same to change the filtering medium; but by employing a settling-chamber and a blow-off pipe connected thereto the impurities 30 may be quickly discharged through the blow-off pipe without stopping the operation of the heater to any appreciable extent. Likewise 35 above the filtering medium lighter impurities are apt to accumulate, and they in like manner may be readily blown off without stopping the operation of the heater.

With the construction of heater herein shown and described the following advantages are obtained:

40 First. The oil is readily separated out of the steam and trapped off.

Second. The escape steam is all forced through the incoming current of water and thereby rapidly condensed in the shelf or pan chamber. A large amount of lime and magnesia or similar mineral impurities are separated out at the point of contact and on the surfaces of the pans and will be caught and held in the pans, and what is not there removed is deposited at the base of the settling-chamber and readily blown off.

Third. By employing a large annular filtering-chamber through which the water passes upwardly into the clear-water chamber but little of the impurities are carried into the filtering medium.

Fourth. A large pure-water chamber is provided, so that all danger of taking off impurities with clear water is avoided.

60 The great desideratum in a feed - water

heater is to condense just as much steam as possible, the more steam condensed the hotter will be the feed-water. By compelling all of the steam to be passed through the streams of incoming water the condensation of the 65 major portion of the steam is obtained.

It will be observed that the system of pans or shelves is simple in construction, but is sustained on a central stand-pipe in such a manner that they may be readily removed 70 therefrom, the pans having one common central support instead of being individually connected to the shell of the heater, which is the common practice in this art. Therefore they are more readily constructed and more easily 75 cleaned and replaced.

Having described our invention, we claim—

1. In a feed-water heater and purifier employing a steam-receiving chamber at the base and a heating-chamber near the top thereof, 80 the combination therewith of a steam-pipe connecting said two chambers, a series of overflow-pans each provided with hollow stems and sockets at their central portion adapted to nest the said series together, means for supporting the same above and athwart the discharge end of the steam-pipe, whereby water supplied to the pans will overflow around the steam-pipe and condense the steam escaping from said pipe, substantially as described. 85

2. In a feed-water heater and purifier, a heating - chamber, an upwardly - extending steam-inlet pipe terminating therein, a vertical tier of pans seated directly on the discharge end of said pipe, each pan having a 95 central socket and stem extending respectively above and below, whereby the pans are detachably superimposed, a water-inlet and a steam-outlet directly above said pans and in line with said steam-pipe, substantially as described.

3. In a feed-water heater and purifier, a heating - chamber, an upwardly - extending steam-inlet pipe terminating therein, a vertical tier of pans seated directly on the discharge end of said pipe, each pan having a central integral hollow socket and stem extending respectively above and below the pan, a rod extending through all of said hollow stems and sockets, a bolt engaging said rod, 105 a water-inlet over the pans, and a steam-outlet over the pans in line with the steam-pipe, substantially as described.

In testimony whereof we have hereunto set our hands.

CHARLES E. TUDOR.
OLIVER B. KAISER.
